CLAIM

The ornamental design for an ear wash basin, as shown and described.

DESCRIPTION

FIG. 1 is a front perspective view of an ear wash basin showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another front perspective view thereof; and,

FIG. 9 is a perspective view thereof showing the ear wash basin in an environment of use.

The broken lines of even length depict portions of the ear wash basin that form no part of the claimed design.

1 Claim, 9 Drawing Sheets
